MACHINE FOR SMOOTHING FASTENERS

Alfred E. Carlile, Meadville, Pa., assignor to Talon,
Inc., a corporation of Pennsylvania

Application January 31, 1939, Serial No. 253,913

7 Claims. (Cl. 80—24)

This invention relates to smoothing devices and particularly to devices for smoothing the rigid (usually metal) elements of composite structures such as slide fasteners of the type shown in Sundback Patent No. 1,219,881.

One of the objects of the invention is to provide a simplified, improved and economical machine for rapidly smoothing the individual surfaces of the rigid elements on such composite structure.

More specifically it is an object of the invention to provide means for smoothing or polishing metal elements of slide fasteners without danger of deforming them.

Another specific object is to smooth the metal elements of slide fasteners without the removal of appreciable quantities of metal therefrom, and without injury to the fabric tapes upon which the elements are mounted.

Another object of the invention is to provide a machine which will operate automatically and at high speed with a minimum of attention.

Other objects and advantages of my invention will appear from the following specification and claims.

In the accompanying drawings I have shown for purposes of illustration one embodiment which my invention may assume in practice.

In the drawings:

Fig. 1 is a plan view of a slide fastener, the elements of which are particularly adapted to be operated on by a machine constructed in accordance with the present invention;

Figs. 2 and 3 are diagrammatic views showing successive stages in the operation of smoothing a fastener element;

Fig. 4 is a fragmentary section on a reduced scale on the line 4—4 of Fig. 3;

Fig. 5 is an enlarged fragmentary side elevation corresponding to Fig. 4 showing the configuration of the grooves in the smoothing rolls;

Figs. 6 and 6a are views of the bottom and end respectively, of an interlocking element before smoothing;

Figs. 7 and 7a are views of the bottom and end respectively, of an interlocking element after smoothing;

Fig. 8 is a plan view showing the general arrangement of a smoothing machine embodying the present invention;

Fig. 9 is a section on an enlarged scale on the line 9—9 of Fig. 8, showing the configuration of the smoothing rolls;

Fig. 10 is a fragmentary section on the line 10—10 of Fig. 9;

Fig. 11 is a section of the entire machine on the line 11—11 of Fig. 8;

Fig. 12 is an end elevation of smoothing roll housing and associated mechanism as seen from the top of Fig. 8;

Fig. 13 is a vertical section of a guide taken on the line 13—13 of Fig. 8;

Fig. 14 is a horizontal section through the guide on line 14—14 of Fig. 13; and

Fig. 15 is a horizontal section on line 15—15 of Fig. 11 showing the lower smoothing rolls and associated guides.

The slide fastener which is selected as an example of the structure to be smoothed by the machine, embodying the present invention as shown in Fig. 1, includes a pair of fabric tapes 20 and 20a having beaded edges 21 to each of which is attached a row of uniformly spaced metallic interlocking elements 22, which as shown in Figs. 6 and 7, includes side surfaces 24 disposed above and below and substantially parallel to the plane of the tape 20. Interlocking elements are connected or disengaged by any suitable slider 25 and the two tapes are ordinarily permanently connected at their lower or closed ends by any suitable end stop 26.

The present invention is primarily concerned with smoothing the side surfaces 24 of the elements before the two tapes 20 and 20a are joined in the relation shown in Fig. 1, and while they are in the form of separate strips, as shown in Fig. 8.

The stringers consisting of the fabric tape and metal interlocking elements, are frequently manufactured by individually cold forging the interlocking elements and attaching them in spaced relation to the beaded edge of the tape by automatic machines. Such machines frequently produce side surfaces 24, as shown in Fig. 6, which are undesirably rough and which have relatively sharp corners 27 at their edges, as shown in Fig. 6a.

Essentially the invention is concerned with smoothing the side surfaces 24 and bevelling or rounding the sharp corners 27. This smoothing may be accomplished by planing or cutting away the rough surfaces, by abrasion, by burnishing or by a combination of these methods. Preferably I burnish the surfaces under pressure, to smooth them without removing metal therefrom at the same time the bevel 28 (Fig. 7) is formed.

To accomplish this, a pair of hardened burnishing rolls 30 and 31 (see Figs. 2, 3 and 9) are mounted on parallel shafts 32 and 33 and are synchronously rotated in opposite directions.

The surfaces of the rolls are spaced slightly apart to permit the passage of an interlocking element between them, the thickness of the elements and the spacing of the surfaces being such as to provide the necessary pressure to accomplish the desired burnishing. Helical lands 35 (Fig. 5) are formed on the surface of each roll providing between adjacent convolutions of the lands helical grooves 36 in which the interlocking elements of the fasteners fit. The thickness of the lands is such that the surfaces of the lands do not contact the fabric of the stringer.

In the operation of the smoothing process, the tape, as shown in Figs. 2 and 3, is held between the rolls by the combined support of the lower roll and the stop or abutment 38. If desired, one or more vanes or supports 37 (Figs. 2, 11) may support the tape 20 and insure its being kept out of contact with the rolls. Such vanes or supports are helpful in feeding the stringers into the rolls.

The rolls are rotated as indicated by the arrows in Figs. 2 and 3, and the abutment 38 holds each individual interlocking element against the force caused by the rotation of the rollers and maintains it between the rollers a sufficient length of time to accomplish the desired burnishing. As shown in Figs. 2 and 3 the abutment is substantially, but not quite parallel to the axes of the rolls, that is, it lies in a plane which is parallel to the axes of the shafts 32 and 33 and as shown in Fig. 15, is inclined with respect to the trace of these axes in the plane of the abutment. The helical lands advance each individual scoop along the abutment as the rolls rotate, and the abutment being inclined with respect to the axes of the rollers, its surface moves farther away from the point of burnishing contact and permits each individual interlocking element gradually to pass through the rollers to the position shown in Fig. 3. Preferably the inclination of the abutment 38 is such that the surface of the abutment is substantially perpendicular to the lands at the point of burnishing.

The space between the convolutions of the lands forms one continuous helical smoothing surface along the entire length of which each element is passed. As it passes along the smoothing surface, it is maintained in line contact therewith, that is, tangential thereto, and the entire side surface of each element gradually passes across this contact line.

As shown in Fig. 5, the grooves between the lands have fillets 40 in their grooves to burnish off the sharp corners 27 and form the rounded or chamfered corners 28, as shown in Figs. 6a and 7a.

The above process may be carried out by any suitable apparatus, one convenient form of which is illustrated in Figs. 8 to 15 inclusive.

It may be desirable in manufacture to join together as the two sides of one complete fastener, two tapes 20 and 20a from the same automatic forging machine and to this end it may be desirable always to keep these two tapes together throughout the manufacturing process. Accordingly, it is convenient to provide two sets of smoothing rollers, one pair of which operates on the tape 20 and the other of which operates on the tape 20a so that the two tapes may be smoothed simultaneously and kept together during this step in the manufacture.

As seen best in Fig. 8, the machine consists of any suitable table or support 50 on which are mounted a pair of supply reels 51, and guides 52 for tapes 20 and 20a. These may be made either

in continuous lengths or as indicated in Fig. 8, a gap as at 53 may be left in which no interlocking elements are applied so that the tape may be cut apart into individual short fasteners.

The smoothing device proper is contained in a casing 54 which includes, as best shown in Fig. 11, the rollers 30 and 31 mounted on their shafts 32 and 33 respectively, and the other pair of rollers 58 and 59, each suitably rotated by a helical gear 60 driven by a gear 61 mounted on a vertical shaft 62 rotated by any suitable means.

The housing 54 consists of a pair of journal blocks 64 and 65 for containing the upper and lower rolls respectively. The journal blocks are adjusted to vary the spacing between the rolls and are locked in such adjusted position by the adjusting nuts 66.

As shown in Figs. 9 and 10, the plate or support 37 of the lower housing 65 extends beyond the end of the lower rolls 31 and 59 and serves as a convenient means for feeding the stringers. As shown in Fig. 15 the plate or support 37 substantially covers the lower rollers 31 and 59 and has a pair of inclined slots 70 adjacent the abutments 38, which slots permit the interlocking elements to drop onto the lower rollers 31 and 59 and into the grooves while the tape is assured of being held out of contact with the rollers by both plates 37.

The helical lands form the means for continuously feeding the fastener strip along the burnishing rolls. In order to provide a continuous feed of fastener strip where a gap 53 occurs and to facilitate the entry of the interlocking elements into the grooves the lower rolls 31 and 59 as shown in Fig. 9 are made longer than the upper rolls 30 and 58. Also in order to assist in the smooth feeding of the fastener strip into the smoothing rollers, a guide, as shown in Fig. 9 is provided above each lower roll and in line with each upper roll. This guide consists essentially of a follower 71 pressed by an adjustable spring 72 in contact with the interlocking elements on the fastener stringer. In order to move the guide out of the way for the initial feeding of the machine, a pin 73 projects from the housing and may be raised by the cam surface 74 on the control bar 75 which is shown in Fig. 12, and may be moved to the left by the bell crank 76 operated by any suitable device, such as the rod 77 connected to a pedal.

The follower 71 forms a vertical guide for feeding the fastener strip to the pair of smoothing rolls. A horizontal guide is also provided for feeding the fastener strip against the abutments 38. This is shown in Figs. 13 and 14 and consists of an inclined plate 78 spaced above the plate 37 to guide the interlocking elements against the inclined abutment as they are fed into the rolls.

Preferably the lower rolls 31 and 59 are provided with adjustable thrust bearings 79 (Fig. 9) to permit any necessary adjustments for aligning the lands of the lower rolls with the lands of the upper rolls at the point of contact with the fastener elements.

If desired, any suitable drag or weight 80, shown in Fig. 8, may be provided for holding the fastener stringers against the plate 37 in order to provide the necessary resistance to effect the desired tension on the tapes in passing through the smoothing rolls.

As shown in Fig. 12 a pipe 85 is provided for delivering any suitable lubricant or coolant to the burnishing rolls. Preferably a suitable coolant, such as soap solution, is continuously cir-

culated. This serves both as coolant and lubricant and does not injure the fabric of the fastener.

In operation the burnishing rolls are rotated at a suitable speed by any suitable driving device. The fastener tapes are fed into the rollers through the guides 71 and 78 described. The surfaces of the burnishing rolls at the bottoms of the grooves form line contacts with the surfaces of the fastener elements at the point at which the rolls are nearest together. For reference this is referred to as the contact line. The rolls rotate in the direction to force the interlocking elements against the inclined abutments 38, and the helical lands continuously feed the interlocking elements along these abutments. As the distance of the abutment from the contact line increases the elements are allowed to pass between the rolls and thus the entire side surface of each interlocking element is progressively fed across the contact line and the entire surface burnished. This burnishing action, it will be observed, takes place by a motion of the burnishing surface in a direction transverse to the line of travel of the fastener chain. The pitch of the helical grooves is such as to feed the fastener slowly along the length of the smoothing rolls so that by the time it has been discharged from the end of the rolls the entire side surface of each interlocking element has been suitably burnished.

While I have described herein one embodiment of my invention, I wish it to be understood that I do not intend to limit myself thereby except within the scope of the appended claims.

I claim:

1. A smoothing device for a slide fastener stringer including a fabric carrier and a series of interlocking elements attached to the carrier and having side surfaces disposed on opposite sides of the carrier, comprising in combination burnishing means defining spaced opposed surfaces engageable simultaneously with opposite side surfaces of the elements and movable with respect thereto for burnishing both side surfaces of each element, and stringer guiding means for supporting the stringer and holding said opposite side surfaces of the elements in contact with the burnishing means while maintaining the fabric carrier out of contact with the burnishing means.

2. A smoothing device for a slide fastener stringer including a fabric carrier and a row of spaced interlocking elements attached to and projecting from the carrier, comprising in combination smoothing means having a smoothing surface, means for guiding the stringer with the interlocking elements in contact with the smoothing surface and the fabric carrier spaced therefrom, means for moving the smoothing surface transversely to the length of the row, and means for moving the interlocking elements along the smoothing means in the direction of the row.

3. A smoothing device for a slide fastener stringer including a fabric carrier and a row of spaced interlocking elements attached to and projecting from the carrier, comprising in combination a rotatable smoothing roll, means for holding the stringer for placing a side surface of the interlocking elements in contact with the circumferential surface of the roll and holding the stringer substantially parallel to the axis of rotation, means for rotating the roll, and means for moving the elements axially along the roll while they are maintained in smoothing contact with the circumferential surface of the roll.
4. A smoothing device for a slide fastener stringer including a fabric carrier and a row of interlocking elements attached to and projecting from the carrier, comprising in combination a pair of smoothing rolls and means for holding the elements between and in line contact with both rolls simultaneously, including a stop arranged to guide the elements for movement progressively across the lines of contact while maintaining opposite side surfaces thereof in smoothing contact with both rolls.
5. A smoothing device for a slide fastener stringer including a fabric carrier and a row of interlocking elements attached to and projecting from the carrier, comprising in combination a smoothing roll mounted for rotation on a predetermined axis, means for guiding a stringer substantially parallel to said axis with the elements in contact with said roll, and a stop for the elements, said stop being in a plane parallel to the axis and disposed along a line in said plane which is inclined to the trace of the axis in the plane.
6. A smoothing device for a slide fastener stringer including a fabric carrier and a row of interlocking elements attached to and projecting from the carrier, comprising in combination a substantially cylindrical smoothing roll having a helical groove defining a helical smoothing surface and slide fastener stringer guiding means for guiding the stringer and holding a plurality of elements simultaneously in contact with different portions of said helical surface.
7. A smoothing device for a slide fastener stringer including a fabric carrier and a row of interlocking elements attached to and projecting from the carrier, comprising in combination a pair of smoothing rolls in substantially vertical alignment, the lower roll being longer than the upper roll, each of said rolls having a substantially cylindrical surface with a helical groove therein defining a helical smoothing surface, and means for guiding said stringer and holding the elements between and in contact with the helical smoothing surfaces of both rolls simultaneously.

ALFRED E. CARLILE.
